WARREN V. JOHNSON AND ROBERT C. KEPNER, OF BERWICK, PENNSYLVANIA, AS
SIGNORS TO AMERICAN CAR AND FOUNDRY COMPANY, OF NEW YORK, N. Y., A COR-
PORATION OF NEW JERSEY

MINE CAR

Application filed June 11, 1931. Serial No. 543,605.

This invention relates to mine cars and contemplates the provision of a welded mine car body which is resiliently supported by wheel axles in such a manner as to be capable of easy and quick removal therefrom.

The invention further contemplates the provision of a new and improved means for mounting or supporting a mine car body.

Another object of this invention is the provision of a new and improved underframe for mine cars.

A further object of this invention is the provision of a mine car comprising a body having an underframe, which body and underframe are detachably mounted on and supported by wheel axles.

A still further object of this invention is the provision of a mine car including a body supported by wheel axles, the latter being mounted in journal boxes having integral upwardly extending spring pockets which extend into spring pocket guides formed as parts of the underframe of the mine car body; the construction resulting in a shock absorbing mounting for the body and permitting easy and quick disassembly of the body from the supporting axles.

Other objects and advantages of this invention will be apparent from the following description taken with the accompanying drawings in which:

Figure 1 is a side elevation of the car of the present invention, certain parts being broken away to more clearly disclose the supporting portions or elements for the body.

Fig. 2 is a top plan view of the mine car of the present invention.

Fig. 3 is an end view of the car, taken at the gate end thereof, and

Fig. 4 is a partial end and sectional view on the line 4—4, Fig. 2.

Referring now more particularly to the drawings in which similar characters of reference designate similar parts in the several views, the car of the present invention comprises a body A mounted on and secured to an underframe B, the body and underframe being carried and supported by axles C supported by wheels D.

As clearly shown, the body A comprises a

bottom or floor 2 formed, in the instance shown, of a single metal plate having its side edges upwardly flanged as at 4 and overlapping the lower edges of side walls 6 and to which the flanges 4 are connected by being welded to the side walls, as shown at 8. The car of this invention is designed for end discharge of lading and hence is provided with an end gate 10 pivoted in ears 12 carried by and preferably welded to the inner surfaces of the side walls 6 at their rear upper corners, as shown more clearly in Fig. 3. For stiffening the side walls 6 the upper edges thereof are outwardly beaded as at 14 and said walls are further provided with vertical posts 16 welded as at 18 to said walls. In the instance shown in the drawings, the posts 16 are shown as straight bars, but obviously within the spirit of the present invention these stiffening posts may assume any preferred or desired form, such as angles, channels, or the like.

The opposite end of the body is closed by a fixed end wall 20, beaded as at 22 along its upper edge and having its lower edge inwardly flanged as at 24 to rest upon and be welded to the bottom 2. For connecting the fixed end wall 20 and the side wall 6, angles 26 are employed which are welded as at 28 to the said side walls and said fixed end wall; the angles 26 serving also as a means for stiffening the body at that end of the body, as will be apparent.

The end gate 10 is provided with a latch 30 adapted to be operated by suitable lever means 31, said latch extending through a horizontal stiffening angle 32 secured, as by welding, adjacent the lower edge of the end gate 10 and into a latch keeper casting 34 forming a part of the underframe as shown more clearly in Fig. 3.

The body just described is mounted upon and secured to the underframe B (see particularly Fig. 4) which latter comprises side sills 36, channel-shaped in the instance shown, to the upper flanges 38 of which the body is connected by suitable fasteners such as the rivets 40. The underframe also includes channel end sills 42 which are connected to the ends of the side sills by welding, or in any manner well-known in the art and which

extend from side to side of the body A to support the latter at its ends; the channel end sills 42 being preferably deeper than the side sills 36 and facing outwardly to support 5 bumpers 44 arranged respectively on each side of the draw bar; it being understood that a draw bar is provided at each end of the underframe.

Connected to the end sills 42 and extending 10 rearwardly therefrom are spaced draft sills 46 between which the draw bars 48 are mounted for movement as shown more clearly in Fig. 2. For stiffeners, gussets 50 are provided which connect the end sills and draft 15 sills, and other gussets 52 are provided for stiffening the connection of the side and end sills (see Fig. 1). The underframe of the car of the present invention also includes spaced cross-bearers indicated generally at 20 D and each formed of spaced channels 54 arranged back to back and extending between the side sills and connected to the latter by suitable means such as the gussets 56 welded thereto; the draft sills 46 extending to said 25 cross-bearers D and being connected to one of the channels forming the same by being welded thereto. The cross-bearers D are connected by a longitudinally arranged channel 58 (Fig. 2) which extends between adjacent 30 channels 54 of the cross-bearers D and is welded thereto in any suitable or desired manner.

Beyond the side sills the body A is also reinforced by angles 60 riveted as at 62 to the bottom; there being two of such elements 60 shown in the drawings, but obviously as many as are required may be provided. The body A is also connected to the cross-bearers D by being riveted thereto as shown at 64.

40 Formed at each end of each of the cross-bearers D is a spring pocket guide indicated generally in Fig. 2 at G and each formed of elements connected to the channels 54, said elements including spaced vertical wear 45 plates 66 welded to the channels 54 and the outer plates 66 resting against and being connected as by welding to the webs of the adjacent side sills. These wear plates 66 are also connected, preferably by welding, to top 50 plates or top spring seats 68, the latter, if desired, being spot welded or otherwise suitably secured to the under surface of the bottom or floor 2.

As clearly shown in Figs. 1 and 4, the axles 55 C extend transversely of the car beneath the car body and underframe and are journalled in journal boxes 70 having upwardly extending integrally formed spring pockets 72 carrying springs 74; the pockets 72 extending 60 into the guides G, see Fig. 4, and the journal boxes having guide lugs 76 adapted to bear against the flanges 78 of guide channels 80, the webs 82 of which latter extend upwardly and lie against the webs of the channels 54 of 65 the cross-bearers and define the remaining

elements which form the spring pocket guides; the webs 82 of said channels 80 being connected in any suitable manner as by welding to the webs of the channels 54 of the cross-bearers. The lower ends of the guide 70 channels 80 are connected by a key 84, as shown clearly in Fig. 1.

From the description herein it is believed that the construction of the car of the present invention will be fully apparent to those skilled in the art. The car of the present invention is so constructed and designed that, should it be desired to remove the body and underframe from the axles it is necessary to remove the keys 84, whereupon the body and underframe may be elevated by means of jacks, or may be lifted by suitable tackle to immediately free the axles from the underframe. The car of the present invention comprises a body formed of metal elements connected together by welding thereby providing a substantially unitary structure, suitably reinforced and strengthened to provide a rugged construction which will withstand service conditions. Further, it will be apparent that due to the specific arrangement of the underframe members including the side sills, cross-bearers, and draft sills, and the connection of the end sills to the side sills and draft sills, buffing shocks received by the bumpers 44 will be transmitted from the end sills to the rugged side sills, thus relieving the body per se, including the floor or bottom 2 and the side walls 6 of the stresses resulting from such buffing shocks. Replacement of parts when occasion demands is comparatively easy and simple to effect.

The drawings herein disclose one embodiment of the invention, but it is to be understood they are for illustrative purposes only and various changes in the form and proportions of the construction shown may be made within the scope of the appended claims without departing from the spirit of the invention.

What is claimed is:

1. In a mine car, a body, an underframe to which the body is secured, said underframe including longitudinally extending sills and spaced cross-bearers, axles beneath the underframe, and journal boxes for the axles, said journal boxes having spring receiving means extending into and guided by the cross-bearers.

2. In a mine car, a body, an underframe to which the body is secured, said underframe including longitudinally extending sills and spaced cross-bearers extending therebetween, wheel axles beneath the underframe, journal boxes in which the axles are journalled, spring pockets carried by the journal boxes and extending into and guided by the cross-bearers, and resilient means in said pockets

for yieldingly supporting the body and underframe.

3. In a mine car, a body, an underframe to which said body is secured, said underframe including side sills and cross-bearers extending therebetween, wheel axles extending transversely of the body beneath the underframe, and means for yieldingly supporting the body relative to the axles to permit relative movement therebetween comprising journal boxes in which the axles are journalled and having parts thereof extended into the cross-bearers, and resilient means interposed between the car body and said extended parts of the journal boxes on which the body rests.

4. In a railway car, the combination with a car body of an underframe to which the body is secured, axles extending transversely of the body beneath the underframe and arranged in a plane lower than the lading supporting bottom of the body, journal boxes for the axles having parts thereof extended into the underframe, and resilient means carried by said extended parts of the journal boxes and on which the body rests to yieldingly support the latter to permit vertical movement thereof relative to the axles.

5. In a railway car, a car body having an end gate, an underframe to which the body is secured, said underframe including side sills and spaced pairs of stiffeners extending therebetween, axles below the underframe, journal boxes for the axles, spring pocket guides formed at each end of said pairs of stiffeners, spring pockets carried by the journal boxes and positioned in said guides, and resilient means in said pockets for yieldingly supporting the body and underframe.

40 6. In a mine car, a body comprising side walls and a fixed end wall welded together, a plate metal bottom to which the side and end walls are welded, an end gate pivotally connected to said side walls, side sills supporting the body and to which the latter is connected, end sills connecting the side sills, spaced pairs of channel stiffeners extending between and connected to the side sills and serving to support the body, and draft sills connected to the end sills and extending rearwardly therefrom to the adjacent channel stiffeners and connected to the latter.

7. In an end dump mine car, a welded body having an end gate and including a plate metal bottom, an underframe to which the plate metal bottom is connected, said underframe including side sills, end sills, cross-bearers, and draft sills between the end sills and cross-bearers, axles beneath the underframe, journal boxes for the axles, spring pockets formed with the journal boxes and extending into the cross-bearers to position the axles, and resilient means in the spring pockets for yieldingly supporting the body and underframe.

8. In a mine car, a body, an underframe on which said body is mounted, spring pocket guides formed with the underframe, wheel axles arranged transversely beneath the underframe, journal boxes for the axles, said journal boxes having spring pockets extending into the spring pocket guides, and yielding means in said pockets for supporting the body and underframe.

9. In a mine car, a body, an underframe on which said body is mounted, said underframe including side sills, end sills connecting said side sills, cross-bearers connecting said side sills, draft sills extending between the end sills and adjacent cross-bearers, and spring pocket guides formed with the cross-bearers.

10. An underframe for mine cars comprising channel side sills, channel end sills extending between and connected to the ends of said side sills, spaced pairs of channels arranged between and connected to said side sills to define cross-bearers, and spring pocket guides formed at each end of each of said cross-bearers, said guides including channel members secured to the webs of the channel members forming said cross-bearers and depending from said cross-bearers to define journal box guides.

11. In a mine car, means for yieldingly supporting the body thereof comprising an underframe including longitudinally extending sills and cross-bearers, spring pocket guides formed with the cross-bearers, journal boxes for the axles of the car arranged between said guide elements and provided with spring pockets projected into said spring pocket guides, and spring means in said pockets for supporting the body.

In witness whereof we have hereunto set our hands.

WARREN V. JOHNSON.
ROBERT C. KEPNER.
